UNITED STATES PATENT OFFICE.

JAMES J. CALOY, OF ST. LOUIS, MISSOURI, ASSIGNOR OF TWO-FIFTHS TO FRANK GENOMI, OF ST. LOUIS, MISSOURI.

RAIL.

1,125,463.

Specification of Letters Patent.

Patented Jan. 19, 1915.

Application filed May 4, 1914. Serial No. 836,304.

To all whom it may concern:

Be it known that I, JAMES J. CALOY, a citizen of the United States, residing at St. Louis, in the State of Missouri, have invented certain new and useful Improvements in Rails; and I do hereby declare the following to be a full, clear, and exact description of the invention, such as will enable others skilled in the art to which it applies to make and use the same.

My invention relates to new and useful improvements in rails, and the object of my invention is to provide a non-spreading rail.

A further object of my invention is to provide a continuous rail composed of an inner member and an outer member adapted to be secured to the inner member to form a rail.

A still further object of my invention is to provide means for securing said members in place.

With these and other objects in view my invention will be more fully described, illustrated in the accompanying drawings and specifically pointed out in the appended 25 claim.

In the accompanying drawings which illustrate a preferred embodiment of my invention, Figure 1 is a side elevation of my improved rail in operative position. Fig. 2 30 is a vertical section through the line 2—2 of Fig. 1.

Referring more specifically to the drawings in which similar reference numerals designate corresponding parts throughout, 35 my rail will be seen to consist of an inner member 1 and an outer member 2. These members are preferably of the same length as the common rail now in use, but may be made in any desired length, without in any 40 way departing from the spirit of my invention. The inner member 1 of my rail is in many respects similar to the rail now in common use, having a head 3, a web portion 4 and flanges 5 and 6. The chief difference 45 resides in the fact that the flange 6 is comparatively narrow. I have also shown the head slightly larger upon the inner side as at 7 and prefer to construct the inner rail member in that manner because of the comparatively great increase in strength thus 50 obtained at the expense of but a slight increase in weight. However it will be understood that this head may be made in the customary or any preferred form without departing in the least from the spirit of my 55 invention.

The outer rail member 2 is adapted to be secured to the outer face of the inner rail member and for that purpose the inner face of this outer rail member is provided adjacent its upper portion with a longitudinal groove 8 and adjacent its lower portion with a longitudinal groove 9, while the central portion of said face is provided with the longitudinal groove 10. By this means the 60 outer member is adapted to bear against the inner member, the outer lower portion of the head of the inner member resting in the groove 8 and the flange 6 of the inner member resting in the groove 9. The lower edge 70 of the outer rail member 2 is extended outwardly to form a longitudinal flange 11 similar to the flange 5 of the inner rail member.

The outer face of the outer rail member 2 is provided with a longitudinal groove 12 having the inwardly diverging faces 13 and 14, the function of this groove being to secure the fish plates 15 in adjusted position. 75

In practice in laying one of the rails of a track a plurality of inner rail members are placed end to end upon the ties and spiked thereto in the customary manner, a plurality of outer members are then placed end to end upon the ties with their inner faces 80 resting against the outer faces of the inner members and with the abutting ends of each joint of the outer rail members at a point intermediate between the ends of an opposing inner rail member. The outer rail members are then secured to the ties in the customary manner and a plurality of fish plates are seated in the groove 12, one fish plate opposite each joint of the inner rail members, when the rail members, both outer 85 and inner, are secured together and to each other by means of a plurality of bolts 16. In practice I prefer to form the outer members and inner members equal in length, in order to avoid all possibility of a joint between the outer members occurring at or near a joint between the inner members. 90 By means of this improved construction the use of fish plates may be entirely done away with if desired, although I prefer to use the same. By making the upper and lower faces of the fish plate receiving groove diverge inwardly the fish plates are firmly 95

secured in place and become ineffective only when all of the securing bolts have been loosened, which is a very uncommon occurrence.

5 It will be seen from the above that I have constructed a composite rail which will effectually prevent all spreading of the rails due to weak joints and which at the same time is simple and easily laid.

10 What is claimed is:

A composite rail comprising an inner rail having a head, a web, an inner flange and an outer stub flange, an outer rail member bearing by its upper portion against the lower portion of the head of the inner rail member and by its lower portion against the outer face of the stub flange, said outer rail member having an inwardly directed flange bearing beneath the head of the inner rail member and engaging against the upper portion of the web of said inner rail member, said outer rail member also having

a second inwardly directed flange resting upon the upper portion of said stub flange and bearing against the lower portion of the web member of the inner rail member, said outer rail member also having an outwardly directed flange corresponding to the flange of the inner rail member, said outer member being also provided with a longitudinal groove in its outer face the opposite faces of which diverge inwardly, fish plates seated in said groove, the upper and lower edges of said fish plates being beveled to bear against the diverging faces of the grooves, and bolts passing through said fish plates, outer rail member and inner rail member and securing the same together.

In testimony whereof, I affix my signature, in the presence of two witnesses.

JAMES J. CALOY.
